LIGHTER FOR GAS BURNERS

Henry F. Alfery, Milwaukee, Wis., assignor to Milwaukee Gas Specialty Company, Milwaukee, Wis., a corporation of Wisconsin

Original application August 31, 1940, Serial No. 354,963. Divided and this application May 16, 1941, Serial No. 393,705

3 Claims. (Cl. 158—115)

This invention relates to lighters for gas burners and has to do particularly with automatic lighters of the type in which there is a pilot burner provided with a torch hood having flash tubes leading to the respective main burners, each tube being adapted when the burner is turned on to convey gas to the pilot burner where it is ignited and the resulting flame flashed back through the tube to light the main burner.

The present application is a division of my copending application Serial No. 354,963, filed August 31, 1940.

One of the main objects of the invention is to provide a lighter of simple, inexpensive and improved construction, and embodying a fuel supply tube for the lighter, having a laterally opening port in the wall thereof, the pilot burner tip being secured to this tube over the port therein, with the interior of the tip positioned to receive fuel from the tube through said port, and preferably with the base of the tip separated from the tube along a portion thereof for the admission of air to said tip.

It is also an object of the invention to provide a simple, inexpensive, and improved mounting of the torch hood on the lighter tube, and particularly an improved mounting in which the lighter tube extends through an opening in the side of the hood and has its outer end flattened together to close the outer end of the tube, with the flattened end of the tube projecting through an opening in the opposite side of the hood, the projecting flattened end of the tube being preferably turned laterally to prevent displacement of the hood along the tube.

Further objects and advantages of the invention will appear from the following detailed description, taken in connection with the accompanying drawing in which:

Figure 1 is a perspective view of a lighter embodying my present invention;

Figure 2 is a fragmentary vertical section on an enlarged scale through the torch hood of the lighter taken substantially on the line 2—2 of Figure 1;

Figure 3 is a vertical section through the lighter tube and pilot tip, taken on the line 3—3 of Figure 2;

Figure 4 is a sectional view through the pilot adjustment valve between the main fuel supply pipe or manifold and the lighter tube; and

Figure 5 is a vertical section taken longitudinally through one of the lighter tubes and showing the injection tip at the outer end of the tube and the adjustable and detachable con-

nection between the inner end of the tube and the torch hood.

Referring now in detail to the drawing, the usual fuel supply pipe or gas manifold is indicated at 10. The gas burner is illustrated fragmentarily at 11 in Figure 1, this burner being fed with fuel from the manifold 10 by the usual feed pipe (not shown) to which air is admitted in the usual way at the end nearest the manifold.

The lighter is provided in appropriate position relative to the burner 11. This lighter comprises a lighter tube 12 connected to the manifold 10 by the pilot adjusting valve 13. The lighter tube 12 leads to the pilot tip 14 which is positioned at an appropriate distance from the burner 11. Although only one burner is shown, it is of course understood that gas ranges for example, embody a number of burners—usually four—and the pilot tip 14 with its torch hood, to be presently described, are disposed centrally between these circularly arranged burners.

The tube 12 extends through an opening 15 in one side of the wall of the small, compact, annular torch hood 16, and the outer end of the wall of the tube 12 is flattened together at 17 to close the outer end of the tube, providing a flat oblong terminal element therefor having its longer axis extending horizontally. The outer flattened end 17 projects through a correspondingly shaped opening 18 in the opposite side of the hood 16, and the projecting flattened end of the tube is preferably turned laterally at 19 (Figure 2) to prevent displacement of the hood 16 from the outer end of the tube 12.

In positions substantially centrally within the annular wall of the hood 16 the top of the tube 12 has a laterally opening port 20. The pilot tip 14 is shown as comprising an outer tip part 21 and an inner tip part 22 having its base secured at 23 to the outer tip part. The inner tip part 22 is of Venturi-like character and is protected by the outer tip part from the heat of the flame which is flashed through the tube to eliminate gum deposits and clogging of the tip. The resulting tip is also wind-proof, i. e., it is of such a character that the pilot will not be accidentally blown out by blasts of air. The top of the inner tip part 22 terminates short of the top of the outer tip part 21 to deliver the fuel into the outer tip part and this outer tip part has a plurality of equally spaced ports 25, one, for example, for each of the flash tubes of the lighter.

The base of the outer tip part is shown as

flanged outwardly at 28, and this base flange is spot-welded at 27 or otherwise suitably secured to the tube 12 on opposite sides of the port 20. The base of the pilot tip is separated from the tube 12 along the intermediate portion adjacent 5 to the port 20 for the admission of air, as shown at 28 in Figure 3. The resulting pilot burner is of the character of a Bunsen burner, and the pilot burns with a blue flame.

Each flash tube—four of these tubes being 10 shown in the drawing—comprises an outer extension tube 30 and an inner swivel tube 31 telescoping over the outer tube. The outer end of the tube 30 has an injection tip 32 spot-welded at 33 (Figure 5) or otherwise suitably secured 15 to the tube. The tip 32, which is adapted to fit in an opening 34 in the burner 11 as shown in Figure 1, has a lateral port 35 for delivering fuel from the burner 11, when the burner is turned on, into the flash tube through an opening 36 in the tube 30 adjacent the port 35. The gas or other fuel thus delivered into the flash tube is conveyed through this tube to the pilot light where it is ignited, and the flame flashes back through the tube and ignites the burner. 20 The telescoping engagement between the tubes 30 and 31 permits adjustment of the injection tip 32 radially with respect to the torch hood. The outer end of each tube 30 is preferably open at 38.

The circular wall of the hood 16 has an in-turned annular retention flange 40 at its upper end, and the bottom of each tube 31 at its inner end has a generally transversely extending slot 42 which, by tilting the outer end of the flash tube upwardly as the device is viewed in Figure 2, is adapted to pass over the flange 40. The opposite ends of the slot 42 are directed generally longitudinally, or the slot is otherwise shaped to form a retention lip 45 along one edge of the slot for interlocking engagement with the flange 40 when the tube is placed in operating position. In its operating position, the flash tube is supported on the flange 40 at the upper end of the torch hood and is held detachably in place by its interlocking engagement with the flange. The resulting connection between the flash tube and the torch hood is of simple, inexpensive, and improved character, and permits not only easy removal of the flash tube for cleaning, but also permits movement of the tube slidingly around the periphery of the hood so that the flash tube may be disposed in any desired radial position. Moreover, the flange and slot connection between the flash tube and the torch hood permits swiveling or swinging movement of the tube in a vertical plane extending substantially through the axis of the hood to raise and lower the injection tip 32 at the outer end of the flash tube to any desired position.

The pilot adjusting valve 13 comprises a valve body threaded into the pipe or manifold 10 and

provided with an inlet 50 leading from the manifold 10, and an outlet 51 leading to the tube 12 which is secured to the valve body by a coupling nut 52. A passage 53 is provided between the inlet 50 and the outlet 51, and a valve screw 54 threaded in the valve body is adapted to be turned to adjust the communication between the inlet and the outlet, and thereby the pilot flame. The inner end of the valve screw 54 preferably has a V-shaped notch 56 or its otherwise formed in a manner to eliminate gum deposits and clogging of the pilot adjusting valve. A nut 58 is preferably provided for locking the adjusting screw 54 in adjusted position.

I do not intend to be limited to the precise details shown or described.

I claim:

1. In a lighter of the class described, a pilot burner, a hood therefor having an opening in one side terminating above its lower edge, and a fuel supply tube for said burner extending through said opening having its end flattened and thereby closed providing a flat substantially oblong terminal element with its longer axis extending horizontally, said hood having an opening in its opposite side terminating above its lower edge substantially conforming to said terminal element, said terminal element projecting through the latter opening and being bent at an angle at the outer face of said hood, said terminal element cooperating with the body portion of said tube and with said hood for confining the latter against relative movement vertically and lengthwise of said tube in either direction.

2. In a lighter of the class described, a hood having openings in its opposite sides, a fuel supply tube extending through said openings supporting said hood and provided with a port opening through its wall within said hood, and a pilot tip seating on said tube over said port to receive fuel therefrom, said tip being secured to said tube at points spaced apart lengthwise thereof and being spaced from said tube between said points providing space for admission of air.

3. A pilot tip assembly for use in a lighter of the flash tube type comprising a hood, a pilot tip within the hood, flash tubes leading from said hood and tip, and a tube for supplying fuel to said burner having a fuel outlet port, said tip comprising an outer member having ports at its upper end to be disposed adjacent the ends of the flash tubes, and an inner member of less height than and disposed in concentric spaced relation to said outer member, said inner member having a base flange closing the lower end of the space between said inner and outer members, said flange being inclined downward and outward of said inner member and defining an upwardly and inwardly tapering fuel and air mixture inlet adapted to overlie the fuel outlet port of the fuel supply tube.

HENRY F. ALFERY.
